CLAIM

The ornamental design for a holder for chopsticks, as shown and described.

DESCRIPTION

FIG. 1 is a perspective view of the holder for chopsticks; FIG. 2 is a side elevational view with the understanding that the other side elevational view is the same;

FIG. 3 is a front elevational view of the holder for chopsticks with the understanding that the other side elevational view is the same;

FIG. 4 is a top plan view with the understanding that the bottom plan view is the same;

FIG. 5 is a perspective view, the broken line showing of chopsticks is environmental only and forms no part of the claimed design.
